UNITED STATES PATENT OFFICE.

OSCAR SWEET, OF SCHENECTADY, NEW YORK.

REFUSE RECEPTACLE.

1,420,391.

Specification of Letters Patent. Patented June 20, 1922.

Application filed April 22, 1921. Serial No. 463,701.

To all whom it may concern:

Be it known that I, OSCAR SWEET, a citizen of the United States, and a resident of Schenectady, in the county of Schenectady 5 and State of New York, have invented certain new and useful Improvements in Refuse Receptacles; and I do hereby declare the following to be a full, clear, and exact description of the invention, such as will enable others skilled in the art to which it 10 pertains to make and use the same.

This invention relates to improvements in refuse receptacles such as ash, trash and garbage cans,--one object of the invention 15 being to so construct such a receptacle that it shall be safe against fire; so that it shall prevent intrusion by animals; so that its contents cannot be accidentally spilled; so that ashes or other refuse can be emptied 20 thereinto without discomfort to the user, and so that the closure of the receptacle may be easily opened or closed without removal, securely fastened when closed and readily adjusted when opened to facilitate 25 the introduction of refuse.

With these objects in view the invention consists in certain novel features of construction and combinations of parts as hereinafter set forth and pointed out in the 30 claim.

In the accompanying drawings, Figure 1 is a view illustrating my invention. Figure 2 is a sectional view, and Figure 3 is a plan view.

35 1 represents a can or receptacle which may be made of metal and of any desired size suitable for receiving any character of refuse, such as ashes, trash and garbage.

The can or receptacle is provided with a 40 closure 2 which is located somewhat below the top of the receptacle and is provided with pintles 3 at diametrically opposite points. These pintles project through horizontal elongated slots 4 in the wall of the 45 receptacle and slightly below the upper edge of the latter. The slots 4 are disposed diametrically opposite each other and in their lower walls, notches 5 are provided to receive the pintles 3. The cover or closure 50 is thus hinged or pivotally supported axially within the upper portion of the receptacle

and is normally prevented from turning in one direction by a latch 6 on said cover or closure and entering a slot 7 in the wall of the receptacle,—said cover or closure being 55 normally prevented from turning in the other direction by means of a stop 8 projecting inwardly from the wall of the receptacle.

It will be observed that when the cover 60 or closure is in normal position there will be no danger of the contents being spilled from the receptacle in the event the latter should be overturned, and it will also be seen that the receptacle will be securely 65 closed against intrusion by animals and against danger from fire in the event that such should occur within the receptacle if hot ashes be discharged thereinto and said receptacle also contains inflammable material.

The cover or closure may be readily unlatched and tilted to permit the introduction of refuse and to further facilitate the discharge of refuse into or from the receptacle, the cover or closure may be slightly 75 raised to remove the pintles from the notches and then moved laterally to enlarge the opening in the top of the receptacle.

Having fully described my invention what 80 I claim as new and desire to secure by Letters-Patent, is:

In a receptacle of the character described, the combination of a body portion having diametrically opposite elongated slots near 85 its top, the bottom wall of each of said slots having a notch intermediate of its ends, a closure located within the receptacle and provided with diametrically opposite pintles entering said slots and mounted normally 90 in said notches, a latch carried by said closure to engage the body portion of the receptacle, and a stop projecting inwardly from the body portion of the receptacle for said closure.

95 In testimony whereof, I have signed this specification in the presence of two subscribing witnesses.

OSCAR SWEET.

Witnesses:

CARL M. CRONK,
BENJ. K. HOFF.
